US0D1110271S

(12) **United States Design Patent** (10) **Patent No.:** **US D1,110,271 S**
(45) **Date of Patent:** **** Jan. 27, 2026**

(54) **ADAPTER FOR DATA TRANSMISSION**

(71) Applicant: **Beijing Unicorn Technology Co., Ltd.**,
Beijing (CN)

(72) Inventor: **Yuanyuan Wu**, Beijing (CN)

(73) Assignee: **BEIJING UNICORN
TECHNOLOGY CO., LTD**, Beijing
(CN)

(**) Term: **15 Years**

(21) Appl. No.: **29/834,481**

(22) Filed: **Apr. 12, 2022**

(30) **Foreign Application Priority Data**

Oct. 29, 2021 (CN) 202130711720.X

(57) **CLAIM**

The ornamental design for a adapter for data transmission, as shown and described.

DESCRIPTION

FIG. 1 is a front and top perspective view of an adapter for data transmission, showing my new design;

FIG. 2 is a rear and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

Portions shown in broken lines form no part of the claimed design.

1 Claim, 7 Drawing Sheets
